(22) **Filed:** **Dec. 17, 2014**

(57) **CLAIM**

The ornamental design for a vehicle, toy, and/or replicas thereof, as shown and described.

(30) **Foreign Application Priority Data**

DESCRIPTION

Jun. 18, 2014 (DE) 40 2014 100 517

This application contains subject matter related to the following co-pending U.S. design patent applications:

(51) **LOC (10) Cl.** **12-08**

Application Ser. No. 29/512,110, filed herewith and entitled “Vehicle, Toy, and/or Replicas Thereof”;

(52) **U.S. Cl.** ..... **USPC** **D12/92**

Application Ser. No. 29/512,111, filed herewith and entitled “Front Bumper for a Vehicle”;

(58) **Field of Classification Search**

Application Ser. No. 29/512,112, filed herewith and entitled “Rear Bumper for a Vehicle”;

USPC D12/86, 90-92, 88; D21/421, 433, 434;

Application Ser. No. 29/512,114, filed herewith and entitled “Rear Bumper for a Vehicle”; and

296/181.1, 181.5

Application Ser. No. 29/512,115, filed herewith and entitled “Side Mirror for a Vehicle”.

CPC B62D 35/00; B62D 25/00; B62D 25/06;

FIG. 1 is a left, front perspective view of a vehicle, toy, and/or replicas thereof according to the design;

B62D 33/00

FIG. 2 is a left side view thereof;

See application file for complete search history.

FIG. 3 is a right side view thereof;
